UNITED STATES PATENT OFFICE.

ORVILLE U. DESHA, OF FORT COLLINS, COLORADO, ASSIGNOR OF ONE-FIFTH TO THE
DESHA TYPELEX TRUST ESTATE, OF FORT COLLINS, COLORADO.

KEY ACTION FOR TYPEWRITER AND OTHER MACHINES.

Application filed March 24, 1927. Serial No. 178,085.

My invention relates to an improvement in key-action for typewriters and other type bar and key-operating machines, actuating means at all times operatively connecting the 5 type bar and key lever moving the type bar to printing point upon depression of the key lever and means reversely breaking the said connection after the printing impact of the type bar for the return of the type bar to its 10 normal position while the key lever is in depressed position; this broad object being the subject matter of an application filed by me on November 5th, 1923, Serial No. 672,871, upon which Patent 1,643,203 issued September 20, 1927, as a contradistinction between 15 previous devices comprising a detachable connection or gap at some point between the key lever and type bar after the latter has been given the movement necessary to effect 20 the printing and before the key lever has completed its movement.

The specific object of the present invention is to provide improved means of the character specified above whereby the reversely breaking 25 actuating connection between the key lever and the type bar is in the nature of a novel operative structure that may readily be incorporated in certain typewriting machines with only slight modification of the structural 30 features of said machines as they now exist.

I have shown my invention embodied, in the present instance, in a typewriter similar to the Underwood standard machine, and in which the invention may be readily incorporated 35 by slight modification of the structural features of the parts involved in effecting such incorporation. It should be understood, however, that the invention is not restricted to use in a machine of this type but 40 may be employed wherever found available.

The desired principle of operation, new mechanical functions, operative expedients, and other objects and advantages will hereinafter be described in the following disclosure and 45 will be more particularly pointed out in the appended claims. In the accompanying drawing wherein like reference characters indicate corresponding parts in the various views.

50 In the drawing, Figure I, is a vertical section of a typewriting machine, one key-action only being shown in normal position; Fig. II represents a view of the key-mechanism similar to Fig. I the key lever being shown depressed and responding the type bar. Fig.

III is also a key-mechanism similar to Fig. I, the key lever being shown in a depressed position and the type bar returned to its normal position. Fig. IV is a skeleton view of the key-mechanism for illustrative purpose in describing the mode of operation of the machine shown. It is understood, of course, that for the sake of clearness and to avoid complication of drawings the applicant has omitted to show the remainder of the key 60 levers and type bars of a complete key board as well as other devices necessary or advisable in a complete machine.

In the embodiment in Fig. I, 1 indicates the frame of a typewriter, 1^a indicating the front and 1^b the rear, having a common power-driven paper carriage 2 supported in the rear on guide rod 3 and in front on guide rod 4; 5 indicates the common platen carried by the paper carriage 2; 6 indicates one of the usual 70 type bars carrying the type 7 at its front end, and having the usual slot 8 at the heel of the rear end, and is arranged to turn on pivot 9 in the form of a segment disposed vertically 75 below the front face of the plate 10 thereby providing the type 7 with a common printing point A as the type bar turns on pivot 9 from normal horizontal position of rest on the segment 11.

12 indicates one of the key levers carrying at the front end finger key 13, the rear end pivoted at 14 to bar 14^a Fig. I, in the rear of the machine, and is kept normally in its elevated position by spring 15 supported by bar 15^a, at normal rest the key lever 12 90 bearing against the underside of bar 20. Key lever 12 is formed with an upward append- 95 ing arm 16, and arranged to provide a saddle-backed seat 17 in front of said arm 16 for the coupling hereinafter described.

The key lever 12 is described as having two incidents of operation, namely; the incident of depression and the incident of release. The incident of depression is disclosed by the movement of the key lever 12 from 100 radius B to radius C, and the incident of release is disclosed by the movement of the key lever 12 back from radius C to radius B. The type bar 6 is described as having two incidents of operation, namely; the incident of 105 response and the incident of recoil. The incident of response of the type bar 6 is disclosed by the movement of the type bar from its initial rest radius E to printing point A, indicated by radius F, forming arc G from 110

5 pivot 9. The incident of recoil of type bar 6 is disclosed by its movement from the printing point A back to normal rest E. These incidents of operation are, of course, present 10 in type bars of nonreversely breaking action in so far as the incident of response E to A of the type bar 6 already known to the art occurs simultaneously with the incident of release, C to B, of the key lever, but, the novelty of my invention relates to the correlation of incidents of operation of the key lever with that of the type bar in providing the operative expedient by which both the, incident of response E to A, of the type bar and 15 the incident of recoil, A to E, occur during the one incident of depression, B to C, of the key lever. This operative expedient is accomplished, in this case, by an improved reversely breaking actuating coupling being 20 the principal subject matter of this application, and comprising the parts connecting the key lever with the type bar, hereinafter described.

18 indicates one of a series of vibratory 25 levers, corresponding in number with the type bars 6 and key levers 12. The vibratory levers 18 are pivoted at 19 in a bar 20 extending across the machine above the key levers 21, and at its upper end each is provided with a 30 pin 21 which engages the cam slot 8 in the heel of the rear end of type bar 6.

The type bar action devised by the applicant includes the reversely breaking actuating coupling comprising the forward thrust link 35 22 and the forward draw link 23, link 22 being connected intermediately of its ends at pivot 25 to the rearwardly projecting arm 18^a of the vibratory lever 18, and link 23 connected at pivot 26 to the upward appending arm 15 of the key lever 12; the couplings 22 and 23 vibrates the vibratory lever 18 forward and moves the type bar 6 to the printing point A upon depression of the key lever 12, and the action includes means hereinafter 40 described for breaking reversely the said coupling after the printing impact of the type bar for the return of the type bar to normal position while the key lever is held depressed.

50 The relative normal positions of pivots 24, 25 and 26 are engaged in a line J J Fig. IV approximately upward in the rear and downward in front relative to key lever 12, disclosing the coupling to be reclining as 55 distinguished from being engaged horizontally or perpendicular to the key lever.

It will be observed that the forward draw link 22 and forward thrust link 23 constituting the reversely breaking actuating coupling operate in a plane above the key lever, disclosed the coupling to be over-slung. Also, it will be noted that the forward draw 60 link 22 and forward thrust link 23 operate in front of the vibratory lever which disclosed the coupling to be forwardly engaged.

27 is a return spring engaging a hole 27^a provided by the rear end of the forward draw link 22 and the other end is supported by bar 27^b which spring serves to turn link 22 on pivot 25 and to hold the vibratory 70 lever 18 normally in operative position as shown in Fig. I, and to return it and the type bar 6 to normal position E after operation.

28 is an extending nose of the forward draw link 22 and is designated as a fulcrum 75 trip nose, pivot 24 being the fulcrum point about which the link 22 turns in cooperating with the saddle-backed seat 17 on top of key lever 12 in lifting link 22 out of said seat 17 and cooperating with stop rod 29 thereby 80 restoring said coupling to normal operative position upon release of key lever 12.

The new mechanical movements and operation thereof are the important factors of the invention in providing the novel function 85 of the key action. A further description of the operative principles, therefore, follows: The geometric circle H H, Fig. IV, with a diametrical line J J from the forward border pivots 24 to the backward border pivot 25 circumscribes what is termed the actuating 90 plane. The diametrical line J J of the actuating plane, from the forward border pivot 24 to the backward border pivot 25 indicates the divert tension line and divides 95 the actuating plane into the upper zone of response K and lower zone of reaction L; the upper zone of response K having to do with the response of the type bar 6 from radius E to radius F as the key lever 12 is 100 being depressed from radius B to radius D; and the lower zone of reaction L having to do with the means for breaking reversely said coupling returning the type bar 6 from printing point A to radius E at rest as the 105 key lever 12 is being continually depressed from radius D to radius C of depression. The normal or idle position of the forward draw link 22 operates in the upper zone of 110 response K as shown in Figs. I and IV. It is necessary that links 22 and 23 be relatively major and minor in length, and link 22 be in such form (in this case curviform) and so engaged in hinge-fold relation so as to permit the pivotal point 26 to oscillate between 115 pivots 24 and 25 in crossing and recrossing the divert tension line J J. Link 22, therefore, is designated as the long link of the coupling, and 23 is the short link. In this case, the elements 22 and 23 of the coupling are folded 120 during the incident of depression from radius B to radius D of key lever 12 simultaneously with the incident of response of type bar 6 from radius E to printing point A; and the hinge-fold elements 22 and 23 unfold 125 during the remainder of depression, radius D to radius C of the key lever 12 simultaneously with recoil of the type bar 6 from printing point A back to radius E.

The saddle-backed seat 17 provided by 130

- the key lever 12 stops pivotal point 24 and effects responsive tension of link 23 under influence of return spring 27 as the key lever is being depressed from radius B to radius D.
- 5 The tension lock of link 23 is also described as contractive tension lock meaning that while the key lever 12 is being depressed, the energy required to respond the type bar 6 effects contractive pressure or forward thrust 10 from pivot 26 to pivot 24 instead of expansive tension or pull. The contractive tension of link 23 stops its oscillation and it moves bodily downward with the key lever 12, as shown in Fig. II, until pivot 26 crosses the 15 divert tension line J J into the lower zone of reaction L. Simultaneously with contractive tension lock of link 23, link 22 operates under expansive tension or forward pull between the forward border pivots 24 20 and the backward border pivot 25 while the key lever is being depressed from radius B to radius D to respond the type bar 6 from radius E to printing point A, and the expansive tension of link 22 being relaxed while 25 the key lever continues the incident of depression from radius D to radius C and simultaneously with the recoil of the type bar 6 from the printing point A back to radius of rest E.
- 30 The correlative operation of links 22 and 23 by the three pivots 24, 25 and 26 breaks reversely the said coupling after the printing impact of the type bar 6 returning it to normal position E while the key lever 12 35 is held depressed in the following manner: A change in relative positions of the border pivots 24 and 25 brings the interior pivot 23 down within the lower zone of reaction L thereby releasing the contractive tension lock 40 of link 23. The release of contractive tension lock of link 23 permits it to resume oscillation about the time the type 7 impacts the printing point A. When link 23 resumes oscillation there being no further obstruction to 45 the recoil of the type bar 6 it immediately recoils from A to E while the key lever 12 continues its incident of depression from D to C and contacting with stop bar 15°.
- It should be understood that the present 50 improvement is capable of a large range of modification within the scope of the invention, and variations may be resorted to within the scope of the invention, and portions of the improvement may be used without others.
- 55 What I claim as new and desire to secure by Letters Patent, is:
1. In a typewriting machine, a type bar, a key lever pivoted at its rear end, a vibratory lever pivoted at its lower end, a rearwardly extending arm provided by said vibratory lever, means operatively connecting the upper end of the vibratory lever with the type bar, a reversely breaking actuating coupling comprising a forward draw link and a forward thrust link forwardly disposed in a 60 plane above the key lever operatively connecting the vibratory lever arm and key lever actuating the vibratory lever forwardly for moving the type bar to printing point upon depression of the key lever, means reversely breaking said coupling after the printing impact to return the type to normal position while the key lever is in depressed position, means restoring said coupling to normal operative position upon release of the key lever. 70
  2. In a type key action, a type bar, a key lever pivoted at its rear end, means operatively connecting the type bar and key lever comprising a vibratory lever pivoted at its lower end, a reversely breaking actuating 75 coupling forwardly disposed across the vibratory lever in a plane above the key lever operatively connecting the vibratory lever and key lever, the elements of said coupling operatively folded moving the type bar to 80 printing point upon depression of the key lever, means unfolding said elements reversely breaking said coupling after printing impact of the type bar, returning the type bar to 85 normal position while the key lever is in depressed position, means restoring the unfolded elements of said coupling to normal operative foldment upon the release of the key lever. 90
  3. In a typewriting machine, a type bar, a key lever pivoted at its rear end, means operatively connecting the type bar and key lever comprising a vibratory lever pivoted at its lower end and disposed vertically and vibrat- 95 ing forwardly, a rearwardly extending arm provided by the vibratory lever intermediately the ends of the latter, a reversely breaking actuating coupling comprising a forward draw link operatively connecting the rearwardly extending arm and a forward thrust 100 link operatively connecting the key lever and said draw link for actuating the vibratory lever forwardly moving the type bar to printing point upon depression of the key lever, means reversely breaking said coupling after 105 printing impact of the type bar for returning the type bar to normal position while the key lever is in depressed position, means restoring said coupling to normal operative position upon release of the key lever. 110
  4. In a type key action, a type bar, a key lever pivoted at its rear end, a vibratory lever pivoted at its lower end, means operatively connecting the upper end of the vibratory lever with the type bar, a rearwardly extending vibratory lever arm provided by the vibratory lever intermediately of the ends of the latter, a reversely breaking actuating coupling comprising a forward draw link pivotally intermediately 115 of its ends to the rearwardly extending vibratory lever arm, a forward thrust link—the forward end thereof operatively connecting the forward end of said draw link, the rear end of said thrust link operatively connecting the key lever for actuating said arm and vibratory lever. 120

tory lever forwardly moving the type bar to printing point upon depression of the key lever, means reversely breaking said coupling after printing impact of the type bar, for returning the type bar to normal position while key lever is in depressed position, means restoring said coupling to normal operative position upon release of the key lever.

5. In a typewriting machine, a type bar, a key lever pivoted at its rear end, a vibratory lever pivoted at its lower end, means operatively connecting the vibratory lever and type bar, a rearwardly extending arm provided by said vibratory lever intermediately the ends 10 of the latter, a reversely breaking actuating coupling comprising a forward draw link and a forward thrust link operatively connecting the key lever and vibratory lever arm, said coupling actuating forward thrust for 15 moving the type bar to printing point upon depression of the key lever, means reversely breaking said coupling after printing impact of the type bar for returning the type bar to normal position while the key lever is in depressed position, means restoring said coupling to normal operative position upon release of the key lever.

6. In a type key action and mechanism, a type bar, a key lever pivoted at its rear end, a vibratory lever pivoted at its lower end, a rearwardly extending arm provided by said vibratory lever intermediately the ends of the latter and providing an upward appending arm intermediately of its ends, a reversely 20 breaking actuating coupling comprising a forward draw link operatively connecting the vibratory lever arm for actuating the vibratory lever forwardly and a forward thrust link pivots connecting to said upward appending arm of the key lever and front end thereof pivoted to the forward end of said draw link actuating the vibratory arm forwardly for moving the type bar to the printing point upon depression of the key lever, means reversely 25 breaking said coupling after printing impact of the type bar returning the latter to normal position while key lever is in depressed position, means restoring said coupling to normal operative position upon release of the key lever.

7. In a type-key action and mechanism, a type bar, a key lever providing an upward appending arm intermediately of its ends, means operatively connecting the type bar 30 and key lever comprising a vibratory lever pivoted at its lower end, a reversely breaking actuating coupling operatively connecting the key lever and vibratory lever comprising a forward thrust link and a forward draw link 35 moving the type bar to printing point upon depression of the key lever, a saddle-backed seat provided by said key lever in front of said upward appending arm, a fulcrum trip nose provided by the front end of said forward draw link extending forwardly and commu-

nicating with the saddle-backed seat reversely breaking said coupling after printing impact of the type bar for returning the latter to normal position while the key lever is in depressed position, means restoring said fulcrum trip nose to normal operative position on said saddle-backed seat upon release of the key lever.

8. In a mechanism and action for a type-key, a type bar, a key lever pivoted at its rear end, means operatively connecting the type bar and key lever comprising a vibratory lever pivoted at its lower end, a reversely breaking actuating coupling operatively connecting the key lever and vibratory lever comprising a forward draw link and a forward thrust link moving the type bar to printing point upon depression of the key lever, means reversely breaking said coupling after the printing impact of the type bar, a return spring horizontally disposed above the key lever and its front end supported by the rear end of the backward draw link, a cross bar in rear of the machine supporting the rear end of said return spring—the contraction of said spring returning the type bar to normal position while key lever is in depressed position, means restoring said mechanism to normal operative position upon release of the key lever.

9. In a typewriting machine, a type bar, a key lever pivoted at its rear end, a vibratory lever pivoted at its lower end and its upper end operatively connecting the type bar, an arm integral with said vibratory lever extending rearwardly intermediately the ends of the latter, a reversely breaking actuating coupling comprising a forward draw link and a forward thrust link operatively connecting the key lever and vibratory lever arm for actuating the vibratory lever forwardly moving the type bar to printing point upon depression of the key lever, means reversely breaking said coupling after printing impact of the type bar to return the type bar to normal position while the key lever is in depressed position, means restoring said coupling to normal operative position upon release of the key lever.

10. In a type-key action and mechanism, a type bar, a key lever pivoted at its rear end, means operatively connecting the type bar and key lever comprising a vibratory lever pivoted at its lower end, a reversely breaking actuating coupling operatively connecting the key lever and vibratory lever comprising a forward draw link and a forward thrust link, a backward border pivot connecting the vibratory lever and draw link intermediately of their respective ends, a forward border pivot connecting the draw link and thrust link, an interior pivot above a line drawn through the border pivots for connecting the thrust link and key lever moving the type bar to printing point upon depression of the key lever, means

actuating the interior pivot downward across a divert tension line between the forward border pivot and the backward border pivot reversely breaking said coupling after printing impact of the type bar for returning the type bar to normal position while the key lever is in depressed position, means restor-

ing said coupling to normal operative position upon release of the key lever.

Signed at Fort Collins, in the county of 10 Larimer and State of Colorado, this 11th day of April, A. D. 1927.

ORVILLE U. DESHA.
